SIGNALING SYSTEM

Maurice B. Long, Glen Ridge, N. J., assignor to
 Western Electric Company, Incorporated, New
 York, N. Y., a corporation of New York

Application October 1, 1926. Serial No. 138,854

9 Claims. (Cl. 250—40)

This invention relates to control of electric circuits or apparatus.

An object of the invention is to control electrical conditions or characteristics of electric circuits or apparatus, as for example, easily and quickly to vary the frequency selectivity of a signal receiving circuit.

A further object is to enable the desired control of the electrical conditions or characteristics of the circuits or apparatus to be effected from a distance.

It is also an object of the invention to facilitate reception of signals, as for example radio signals, and operation of a sound reproducing device, as for example a phonograph, alternatively.

Another object is to facilitate the association of sound reproducing apparatus, or amplifying and reproducing apparatus, with either a mechanically operated electrical pick-up device or an electrically operated pick-up device.

It has been suggested that, where a radio system is linked with a wire system, for tuning a radio transmitting circuit from a distance, relays

be provided to control a variable inductance in the antenna circuit and control the connection and disconnection of variable condensers in the circuit which feeds the antenna circuit, and for tuning a radio receiving circuit from a distance, relays control the connection and disconnection of variable condensers in the circuit fed by the receiving antenna. The relays in each case may be controlled by rotary switches and other relays which are operated over wires when a call is originated from a subscriber's station.

As examples of applications of the present invention there are disclosed herein several simple radio receiving systems embodying specific forms of the invention. In accordance with this invention, condensers in the receiving antenna circuit and condensers in the circuit fed from the antenna circuit are adjusted at the receiver or at a distance therefrom, for tuning the receiver. The adjustment may be effected by a series of keys or a series of keys and relays, or by rotary selector switches.

In accordance with the invention, in order to substantially instantaneously tune a radio receiver to select wave lengths of, say, a few first class local radio broadcasting stations, station selecting keys or switches may be operated, the operation of each switch causing a different predetermined value of tuning capacity to be inserted substantially instantaneously in the tuning circuit of the receiver. In order that the receiver

may be prepared for this instantaneous tuning to whatever wave lengths the local stations just mentioned may have, these tuning capacities, which for convenience may be termed instantaneous tuning capacities are adjustable. The station selecting keys may be locking keys, the operation of each causing the release of the key last operated. The receiver, without suffering disturbance of its adjustment for the instantaneous tuning just mentioned, may be tuned to any one of a range of wave lengths, including the wave lengths of the several local stations mentioned above, by means of an additional variable condenser, this condenser being connected in the tuning circuit by operation of an additional locking key. Upon operation of this key the station selecting key last operated is released, and disconnects its tuning capacity from the tuning circuit. Operation of any station selecting key when the above mentioned additional variable condenser is in circuit releases the above mentioned additional key, thus causing the additional variable condenser to be withdrawn from the tuning circuit.

According to another aspect of the invention a selector switch may be used to control the connection of the instantaneous tuning elements. If desired, the tuning of the radio receiver may be controlled from a point distant from the instantaneous tuning capacities, as for example by having selecting means at a telephone receiver which is operated by the radio receiver and is at a distance from the instantaneous tuning capacities and having the selector control the switching of the tuning capacities in and out of circuit.

Craft Patent No. 1,559,679, November 3, 1925, discloses a system in which a common loud speaker, together with its amplifier, may be connected to the output of a radio receiving circuit or to an electric phonograph, as desired. The switching operation is accomplished by means of a three position switch so that it is possible to have the loud speaker connected to the radio apparatus or to the phonograph, or entirely disconnected.

In a specific embodiment of the instant invention, there is an electrical pick-up device adapted to be mechanically operated by a phonograph record and an electrical pick-up device, such as a radio receiver, both of which are adapted to be separately associated with a common amplifying element and a loud speaker by means which are automatically controlled by the phonograph operating mechanism to bring about the alternative connection and disconnection of the two

with the amplifying apparatus. It will be understood that the amplifier may be dispensed with where sufficient volume of reproduction is obtainable without it.

5 Other objects and features of the invention will be apparent from the following description and claims:

Fig. 1 of the drawings is a diagram of a radio receiving system embodying one form of the invention; Fig. 2 is a diagram of a radio receiving system embodying another form of the invention; and Fig. 3 is a diagram of a radio receiving system embodying still another form of the invention.

In Fig. 1 there is an antenna 5, an inductance 6, and three optional or alternative paths to ground from inductance 6. Relays 7 and 8 controlled by keys or push buttons 9, 10, 11 and 12, are adapted to connect any one of these paths in the antenna circuit. Of 10 these paths, one includes a variable condenser 15 and a coil 18, a second includes a variable condenser 16 and a coil 19, and the third includes a variable condenser 17 and a coil 20. These three coils constitute the primary windings of a coupling coil 21, the secondary winding 22 of which forms part of the tuned input circuit of a radio receiver. This input circuit may be tuned by any one of three condensers 15', 16' and 17' optionally or alternatively connected in circuit by the relays 15 20 25 30 35 40 45 50 55 60 65 70 75 80 85 90 95 100 105 110 115 120 125 130 135 140 145 150

The radio receiver comprises an electric space discharge detector tube 24 feeding an electric space discharge amplifier tube 25 through an audio frequency transformer 26 and the left hand contact of an electromagnetic switch 27, an electric space discharge amplifier tube 28 fed from tube 25 through an audio frequency transformer 29, and a loud speaking telephone receiver 30 fed from tube 28 through a transformer 31, the right hand contact of an electromagnetic switch 32 and an adjustable volume control or voltage changing device 33. As indicated by conductors 34, other volume control devices and loud speakers may be connected to the output side of transformer 31 and located at any desired places.

A battery 40 supplies filament heating current for tubes 24 and 25 through the left hand inner contact of a relay 42, left hand contact of relay 32, filament of tube 25, filament of tube 24, and a resistance 45. Steady potential for the grid of tube 25 is supplied by the voltage drop in the filament of tube 24 and in resistance 45.

An alternating current source 46 supplies current to the primary winding of a transformer 47. Current is also supplied from source 46 to the primary windings of transformer 48 and transformer 49 through the right hand outer contact of relay 42. The secondary winding of the transformer 47 supplies current for operating relays 7, 8, 42 and 32 through keys 9, 10, 11 and 12.

A secondary winding 50 of transformer 48 has its mid-point grounded and supplies alternating current for heating the filament of tube 28.

Alternating current from a secondary winding 51 of transformer 48 is rectified in a circuit extending from winding 51 through choke coil 52, resistances 55, 56 and 57 to earth, thence through conductor 60, resistance 65, conductor 66, the space discharge path of an electric space discharge rectifier tube 67, to winding 51. A portion of winding 51 supplies alternating current for heating the filament of rectifier tube 67. The voltage drop in resistance 65 is applied as steady potential to the grid of tube 28, through a resist-

ance 68 and the secondary winding of transformer 29.

The voltage drop across resistance 57 is applied as steady potential to the plate of tube 24, through the primary winding of transformer 26.

The voltage drop across resistances 56 and 57 is applied as steady voltage between the plate and the filament circuit of tube 25, through the primary winding of transformer 29.

The voltage drop across resistances 55, 56 and 57 is applied as steady voltage between the plate and the filament circuit of tube 28, through the primary winding of transformer 31.

The choke coil 52 and the condenser 70 reduce voltage fluctuations across resistances 55, 56, 57 and 65. A condenser 71 further reduces voltage fluctuations across resistances 55, 56 and 57. A condenser 72 further reduces voltage fluctuations across resistances 56 and 57. A condenser 73 further reduces voltage fluctuations across resistance 57. Resistance 68 and a condenser 74 further reduce voltage fluctuations applied from resistance 65 between the grid and the filament of tube 28, without substantially reducing the steady voltage applied from resistance 65 to that grid. Condensers 71, 72 and 73 also provide paths of low impedance to signaling currents in the plate circuits of tubes 28, 25 and 24 respectively.

As indicated by the broken lines representing conductors leading from the set of keys 9, 10, 11 and 12, this set of keys may, if desired, be remote from the condensers 15, 16, 17, 15', 16' and 17', the connection of which to the receiver circuit they control. For example, this set of keys 105 may be located with a loud speaking telephone receiver (not shown) connected to the conductors 34 at a distance from the condensers, the tubes 24, 25 and 28 and the loud speaker 30. As indicated by conductors 75, other sets of keys (not 110 shown) like the set constituted by keys 9, 10, 11 and 12 may be employed, the keys 9, 10, 11 and 12 being connected in multiple with the corresponding keys, respectively, of each of such other sets. Such other sets may be located at any desired 115 places. For example, one set may be near the tuning condensers and the loud speaker 30.

Pilot lamps such as 76 are connected to the secondary winding of transformer 49, the primary winding of which is connected directly in 125 parallel with the primary winding of transformer 48. Each of these lamps may be located at any desired place and indicates whether the source 46 is supplying E. M. F. to the transformer 48.

The armature of each of the relays 7, 8 and 42, in the absence of current in the windings of the relay, is held in the position to which it was last operated by one of its windings. A holding spring is shown for each of these relays, as representing means for thus holding the armature. The winding of relay 32 is continuously connected in series with the secondary winding of transformer 47. Relay 32 is therefore momentarily operated whenever one of the keys 9 to 12 is momentarily operated or, in other 130 words, whenever either of the windings of relay 7, 8 or 42 is energized. In opening, relay 32 quickly opens its right hand contact, to disconnect from the secondary winding of transformer 31 the volume control devices and loud speakers 135 such as 33 and 30, and thereafter opens at its left hand contact the filament heating circuit of tubes 24 and 25. In closing, relay 32 first closes its left hand contact and thereafter closes its right hand contact. The operation of the relay 140

32 prevents the production of noise in the loud speakers due to the action upon the input circuits of tubes 24 and 25 of stray fields from the windings of relays 7, 8 and 42 when those windings are switched in or out of circuit by keys 9 to 12. The relay opens the circuit of the secondary winding of transformer 31 before the stray field has time to change materially; and the cooling of the filaments of tubes 24 and 25 due to the opening of the filament circuit at relay 32 renders the tubes inoperative until the stray field has again reached a substantially steady state.

Each of the coils 18, 19 and 20 is, independently of the others, variably coupled to the coil 22.

To adjust the system so that it may substantially instantaneously be set to selectively receive signals transmitted on waves of any of three different wave lengths, say signals from three broadcasting stations J, K and L (not shown) from which it will be desired to receive signals more often than from other stations, key 9 is first closed momentarily. Thereupon, the left hand winding of relay 7, the right hand winding of relay 42 and the winding of relay 32 are energized over a circuit extending from the secondary winding of transformer 47 through the winding of relay 32, key 9, a resistance 79, left hand winding of relay 7, and right hand winding of relay 42. Relay 32 operates momentarily. Relay 7 operates, or remains operated, to the left, remaining in that position after key 9 is released. Relay 42 operates, or remains operated, to the right, remaining in that position after key 9 is released. With relay 42 so operated, the filament circuit of tubes 24 and 25 and the circuit of the primary windings of transformers 48 and 49 are closed at its contacts. With relays 7 and 42 so operated, the antenna circuit extends from antenna 5 and coil 6 through the outer left hand contact of relay 7 condenser 15 and coil 18 to ground; and the inner right hand contact of relay 7 connects condenser 15' across coil 22. Condensers 16, 17, 16' and 17' and coils 19 and 20 are thus out of circuit. Now by adjusting condensers 15 and 15' the system can be tuned to the wave length of, say, station J. Also, the coupling between coils 18 and 22 may be properly adjusted for the intensity of the waves received by antenna 5 from station J. The system is then conditioned for receiving signals from station J, and thereafter if the operator has changed it to a condition for receiving signals of other wave lengths or to a condition in which it is not responsive to signals of any wave length, it can substantially instantaneously be conditioned for receiving signals from station J by merely depressing key 9 momentarily.

The system having been adjusted so that it can substantially instantaneously be set to selectively receive from station J, it may next be adjusted so that it can similarly be set to receive from station K. To so adjust it, key 10 is first closed momentarily. Thereupon a circuit is momentarily established extending from the secondary winding of transformer 47 through the winding of relay 32, key 10, the left hand winding of relay 8, the right hand winding of relay 7, and the right hand winding of relay 42. Consequently, relay 32 operates momentarily, and relays 7, 8 and 42 operate or remain operated to the right, the left and the right, respectively, remaining in those positions after key 10 is released. With the relay 42 so operated to the right, the filament circuit of tubes 24 and 25 and

the circuit of the primary windings of transformers 48 and 49 are closed at its contacts. With relays 7 and 8 so operated, the antenna circuit extends from antenna 5 and coil 6 through the inner left hand contact of relay 7, the outer left hand contact of relay 8, condenser 16 and coil 19 to ground; and condenser 16' is connected across coil 22 through the inner right hand contact of relay 8 and the outer right hand contact of relay 7. Condensers 15, 17, 15' and 17' and coils 18 and 20 are then out of circuit. Now by adjusting condensers 16 and 16' the system can be tuned to the wave length of station K. Also, the coupling between coils 19 and 22 can be properly adjusted for the intensity of the waves received by antenna 5 from station K. The system is then adjusted for receiving signals from station K, and thereafter, if the operator has changed it to a condition for receiving signals of other wave length or to a condition in which it is not responsive to signals of any wave length, it may be substantially instantaneously conditioned for receiving signals from station K by merely depressing key 10, momentarily.

The system having been adjusted so that it can substantially instantaneously be set to selectively receive signals from station J or station K, it may next be adjusted so that it may similarly be set to receive from station L. To so adjust it, key 11 is first closed momentarily.

Thereupon a circuit is momentarily established, extending from the secondary winding of transformer 47 through the winding of relay 32, key 11, right hand winding of relay 8, right hand winding of relay 7, and right hand winding of relay 42. Consequently, relay 32 operates momentarily and each of relays 7, 8 and 42 operates, or remains operated, to the right, remaining so operated after key 11 is released. With the relay 42 so operated, the filament circuit of tubes 24 and 25 and the circuit of the primary windings of transformers 48 and 49 are closed at its contacts. With relays 7 and 8 so operated, the antenna circuit extends from antenna 5 and coil 6 through inner left hand contacts of relays 7 and 8, condenser 17 and coil 20, to ground; and condenser 17' is connected across coil 22 through the outer right hand contacts of relays 7 and 8. Condensers 15, 16, 15' and 16' and coils 18 and 19 are then out of circuit. Now by adjusting condensers 17 and 17' the system can be tuned to the wave length of station L. Also, the coupling between coils 20 and 22 can be properly adjusted for the intensity of the waves received from station L. The system is then adjusted for receiving signals from station L, and thereafter if the operator has changed it to a condition for receiving signals of other wave length, or to a condition in which it is not responsive to signals of any wave length, it may substantially instantaneously be conditioned for receiving signals from station L by merely depressing key 11 momentarily.

At any time, the system may be rendered unresponsive to signals of any wave length by depressing key 12 momentarily, whereby there is established momentarily a circuit extending from the secondary winding of transformer 47 through relay 32, key 12, a resistance 80, and left hand winding of relay 42. Upon establishing this circuit, relay 32 operates momentarily, and relay 42 operates to the left to break the filament circuit of tubes 24 and 25 and the circuit of the primary windings of transformers 48 and 49.

Thereafter, as indicated above, key 9, 10 or 11

may be operated whenever it is desired to tune the system, substantially instantaneously to the wave length of station J, K or L, respectively.

Resistances 79 and 80 enable each of the windings of relays 7, 8, 42 and 32 to have the same constants and yet receive the same value of operating current from transformer 47, resistance 79 having an absolute impedance substantially equal to that of one of said windings, and resistance 80 having an impedance twice the value of that of resistance 79.

The condensers 15, 16, 17, 15', 16' and 17' may be of any suitable type, as for instance, rotary plate, air dielectric condensers of ordinary type, and one pair of these condensers may be varied or adjusted to tune the receiver to any desired one of a range of wave lengths, including the wave lengths of the stations to which the receiver is instantaneously tuned by the other pairs. This variation of the capacities of the one pair of condensers will not disturb the adjustment of the receiver for the instantaneous tuning by the other pairs, since the operation of a key for causing either of the other pairs to be connected in circuit causes the one pair to be withdrawn from circuit.

If desired, the constants of the antenna circuit or of the circuit fed thereby may be maintained fixed, the tuning of the receiver being accomplished by varying only one of these circuits.

A phonograph 85 has a reproducer 86 and has start-stop mechanism represented, by way of example, by a brake 87. The start-stop mechanism when in position to prevent motion of the phonograph turntable opens a switch 89 to maintain relay 27 deenergized. The grid or input circuit of tube 25 is then closed through transformer 26, at the left hand contact of relay 27, in order that the radio receiver may be operated to reproduce radio signals received by antenna 5. When the start-stop mechanism is in position to allow the phonograph to operate, switch 89 is closed, and, provided relay 42 is closed to the right, relay 27 will be energized over a circuit extending from battery 40 through left hand contacts of relays 42 and 32, winding of relay 27, and switch 89 to battery 40. This energization of relay 27 disconnects the transformer 26 from the grid of tube 25, so that the radio receiver will not operate to reproduce radio signals received by antenna 5 during the time that the phonograph is operating. However, the radio receiver will automatically be rendered operative to reproduce the radio signals when the phonograph is stopped by the brake 87. The reproducer 86 is of the electrical type and is connected to the primary winding of a transformer 90, the secondary winding of which is adapted to be connected between the grid and the filament of tube 25 by a front contact on relay 27. Thus, when the phonograph is operating, its electrical output from reproducer 86 is amplified by tubes 25 and 28 and converted into sound by the loud speakers such as 30.

Obviously, if desired, an acoustic phonograph may be employed and the break operated switch 89 used only to control the radio receiver in response to the starting or stopping of the phonograph.

Referring now to Fig. 2, an antenna circuit is shown, comprising an antenna 105, a variable inductance 107 and a variable condenser 100 connected to ground. A plurality of variable condensers such as 110, 111, 112 and 113 are ar-

ranged to be optionally connected in shunt relation to condenser 110 by the operation of locking keys, such as 120, 121, 122, and 123. Each of the keys upon being operated, is locked in closed position by a locking bar or member 129 which is urged to its locking position by a spring 131. Also, each of the keys, upon operation, releases the key last operated, the released key thereupon being returned to its open position by a spring such as 132.

The coil 107 is magnetically coupled to a coil 140, which forms part of a tuned input circuit for an electric space discharge tube 145 which may be a detector having its grid maintained at the proper biasing potential by the usual blocking condenser 146 and leak resistance 147. The output circuit of the tube includes an indicating device, as for example, a telephone receiver 150. The tuned input circuit of the tube includes a variable condenser 100' shunted across coil 140, and adapted to have a plurality of variable condensers such as 110', 111', 112' and 113' optionally connected in shunt relation thereto by the keys 120 to 123. Condensers 100, 100', 110, 111, 112, 113, 110', 111', 112' and 113' may be, for example rotary plate, air dielectric condensers of ordinary type.

To adjust this system so that it may substantially instantaneously be set to selectively receive signals transmitted on waves of any one of four different wave lengths, say signals from four broadcasting stations, J, K, L and M (not shown) from which it will be desired to receive signals more often than from other stations, key 120 is first depressed, releasing all of the keys 121 to 123. When keys 120 to 123 have thus been operated, condensers 111 to 113 and 111' to 113' are out of circuit, and condensers 110 and 110' are in parallel relation to condensers 100 and 100', respectively. The circuit for condenser 110 extends from the lower plate of condenser 100, through inner right hand contacts of keys 123, 122 and 121 in series, and condenser 110, to ground. The circuit for condenser 110' extends from the upper plate of condenser 100', through inner left hand contacts of keys 123, 122, and 121 in series, and condenser 110', to ground. With condensers 100 and 100' in any desired setting, condensers 110 and 110' may now be adjusted to tune the system to, say, the shortest of the wave lengths of the four stations, as for example the wave length of station J. Thereafter, whenever the operator has changed the station to a condition for receiving signals of other wave length by operation of any of the keys 121, 122 or 123 as about to be described, it can substantially instantaneously be conditioned or set for receiving signals from station J by merely depressing key 120, provided the setting of condensers 100 and 100' has not been changed.

The system having been adjusted so that it can substantially instantaneously be set for receiving from station J, it may next be adjusted so that it can substantially instantaneously be set to receive from station K. To so adjust it, key 121 is depressed. Thereby condenser 111 is connected in parallel relation to condenser 100 through a circuit extending from the lower plate of condenser 100, through the inner right hand contacts of keys 123 and 122, the outer right hand contact of key 121, and condenser 111, to ground. At the same time, condenser 111' is connected in parallel relation to condenser 100', through a circuit extending from the upper plate of condenser 100' through inner left hand contacts of keys 123 and 122, the outer right hand contact of key 121, and condenser 111', to ground.

123 and 122, outer left hand contact of key 121, and condenser 111', to ground. Condensers 110, 112, 113, 110', 112' and 113' are now out of circuit, and, condensers 100 and 100' remaining in their former setting, condensers 111 and 111' may now be adjusted to tune the system to receive from station K. Thereafter whenever the operator has changed the system to a condition for receiving signals of other wave length by operation of keys 122 or 123 as described below or by operation of key 120 as described above, the system can substantially instantaneously be conditioned for receiving signals from station K by merely depressing key 121, provided the setting of condensers 100 and 100' has not been changed.

The system having been adjusted so that it can substantially instantaneously be set for selectively receiving from stations J and K, it may next be conditioned so that it can similarly be tuned to receive from station L. To so condition it, key 122 is depressed. Thereby condenser 112 is connected in parallel relation to condenser 100 through a circuit extending from the lower plate of condenser 100, through inner right hand contact of key 123, outer right hand contact of key 122, and condenser 112, to ground. At the same time condenser 112' is connected in parallel relation to condenser 100' through a circuit extending from the upper plate of condenser 100', through inner left hand contact of key 123, outer left hand contact of key 122, and condenser 112', to ground. Condensers 110, 111, 113, 110', 111' and 113' are now out of circuit, and, condensers 100 and 100' remaining in their former setting, condensers 112 and 112' may now be adjusted to tune the system to receive from station L. Thereafter, whenever the operator has changed the system to a condition for receiving signals of other wave length by operation of key 123 as described below or by operation of key 120 or 121 as described above, the system can substantially instantaneously be set for receiving signals from station L by merely depressing key 122, provided the setting of condensers 100 and 100' has not been changed.

The system having been adjusted so that it can substantially instantaneously be set for selectively receiving from stations J, K and L, it may next be conditioned so that it can likewise be tuned to receive from station M. To so condition it, key 123 is depressed. Thereby condenser 113 is connected in parallel relation to condenser 100 through a circuit extending from the lower plate of condenser 100, through outer right hand contact of key 123, and condenser 113, to ground. At the same time, condenser 113' is connected in parallel relation to condenser 100' through a circuit extending from the upper plate of condenser 100' through outer left hand contact of key 123, and condenser 113', to ground. Condensers 110, 111, 112, 110', 111' and 112' are now out of circuit, and, condensers 100 and 100' remaining in their former setting, condensers 113 and 113' may now be adjusted to tune the system to receive from station M. Thereafter whenever the operator has changed the system to a condition for receiving signals of other wave length by operation of key 120, 121 or 122 as described above, the system can substantially instantaneously be set for receiving signals from station M by merely depressing key 123, provided the setting of condensers 100 and 100' has not been changed.

Condensers 100 and 100' may be varied to thereby tune the system in the ordinary way to any number of frequencies; but they must again

be given the settings which they had while the system was being adjusted so that certain stations could be selected by depressing keys 120 to 123, when it is desired to select those stations in that manner.

If desired, condensers 100 and 100' may be omitted from the system of Fig. 2, the capacity settings of the condensers controlled by keys 120 to 123 then being made such that the capacities of those condensers serve as the total capacities for tuning the system to receive the signals for which the keys are to condition the system. Whether or not the condensers 100 and 100' are omitted from the circuit or adjusted to their zero capacity settings, one pair of the condensers 110 to 113 and 110' to 113' may be varied or adjusted to tune the receiver to any desired one of a range of wave lengths, including the wave lengths of the stations to which the receiver is instantaneously tuned by the other pairs. This variation of the capacities of the one pair will not disturb the adjustment of the receiver for the instantaneous tuning by the other pairs, since the operation of a key for causing any of the other pairs to be connected in circuit causes the one pair to be withdrawn from circuit.

If desired, the constants of the antenna circuit or of the circuit fed thereby may be maintained fixed, the tuning of the receiver being accomplished by varying only one of these circuits.

Referring now to Fig. 3, an antenna circuit is shown comprising an antenna 305 connected to ground through a tuning inductance 306, tuning condensers 307 adapted to be optionally or alternatively connected in the circuit, and an inductance coil 308. The latter coil is variably magnetically coupled to a tuning and coupling coil 310 which forms part of a tuned input circuit for an electric space discharge tube 315 which may be a detector having its grid maintained at the proper biasing potential by the usual blocking condenser 316 and leak resistance 317. The output circuit of the tube includes an indicating device, for example a telephone receiver 320. The tuned input circuit of the tube includes condensers 325' adapted to be optionally connected in shunt relation to portions of coil 310 by a contact finger 325 movable over a bank of contacts of a rotary selector switch 326 such as is commonly employed in machine switching telephone circuits. This selector switch also comprises contact fingers 330, 335, 340 and 345 and their banks of contacts, a stepping magnet 350 for driving the common shaft of all of the contact fingers, and a dialing device or circuit interrupting switch 355 for interrupting the circuit through a battery 360, winding of magnet 350 and device 355 in order to automatically generate impulses corresponding in number to any numeral dialed for operating the magnet. Whenever the contact finger 345 is off of its normal or extreme left hand contact, it may be returned to the normal contact by operating key 365 to close a circuit extending from ground through battery 360, winding and contact of magnet 350, finger 345 and its contacts, and key 365, to ground. The magnet 350 alternately breaks and makes this circuit until finger 345 reaches its normal contact, when the key 365 may be released. As indicated by the dotted portions of the lines representing conductors extending to the indicating device 320 and the devices 355 and 365, those devices may, if desired, be remote from the other apparatus of the system.

The finger 335 is adapted to connect con-

densers 307 optionally in the antenna circuit. The finger 330 is adapted to vary the portion of inductance coil 306 included in the antenna circuit, and the finger 340 is adapted to vary the portion of inductance coil 310 included in the tuned input circuit of tube 315. Thus the fingers 325, 330, 335 and 340 all cooperate in selecting the tuning reactances for tuning the system to selectively receive waves of desired frequency.

10 The condensers 307 and 325' may be adjusted to tune the system to a different selected frequency for each position of the selector switch, and thereafter, the system can be tuned for receiving any desired one of these frequencies, when not already tuned to the desired one, by closing key 365 long enough to permit the selector switch to step to its normal position and then dialing a numeral corresponding to the 15 number of steps which the selector switch must take to move from its normal position to the position in which it will select the requisite reactances for the desired tuning.

What is claimed is:

25 1. A circuit capable of operating at any frequency in a range of frequencies comprising means for substantially instantaneously rendering said circuit selective at will to waves of any desired one of a plurality of predetermined 30 frequencies within said range, and means for rendering said circuit selective at will to waves of any desired frequency within said range of frequencies.

35 2. A circuit comprising means for substantially instantaneously rendering said circuit selective to waves of any desired one of a plurality of predetermined frequencies, and means for rendering said circuit optionally selective to waves of any desired frequency in a range of frequencies including a substantial portion of the frequency range between the lowest and the highest of said predetermined frequencies.

40 3. A circuit comprising means for substantially instantaneously rendering said circuit selective at will to waves of any desired one of a plurality of predetermined frequencies, and means for rendering said circuit selective at will to waves of any desired frequency in a range of frequencies, including at least two of said predetermined 45 frequencies, and means for varying the value of one of said predetermined frequencies at will.

45 4. A signal receiving circuit comprising tuning reactances for use in tuning said circuit to selectively receive waves of any one of a plurality of frequencies, reactance selecting holding keys and circuit connections whereby operation of each key causes a different part of said reactances to be rendered effective in tuning said circuit, a variable reactance for tuning said circuit to selectively receive any desired frequency of a given frequency range, an additional holding key and circuit connections whereby operation of said additional key causes said variable reactance to be rendered effective in tuning said circuit, and means responsive to the operation of any one of said holding keys to cause restoration of the one already operated, whereby the circuit may instantaneously be tuned to any one of said plurality of frequencies by the operation of the respective one of the first mentioned holding keys or be conditioned for variable tuning by the operation of said additional holding key.

50 5. A signal receiving circuit comprising tuning capacities, each adjustable in value, for use in

tuning said circuit to selectively receive waves of any one of a plurality of frequencies, capacity selecting locking keys and circuit connections whereby each key upon operation renders a different part of said capacities effective in tuning said circuit, a variable condenser for tuning said circuit to selectively receive any desired frequency of a given frequency range, an additional locking key and circuit connections whereby said additional key, upon operation, renders said variable condenser effective in tuning said circuit, and means effective upon the operation of any one of said locking keys to release the one already operated, whereby the circuit may instantaneously be tuned to any one of said plurality of frequencies by the operation of the respective one of the first mentioned locking keys or be conditioned for variable tuning by the operation of said additional locking key.

55 6. A signal receiving circuit comprising tuning reactances for use in tuning said circuit to selectively receive waves of any of a plurality of frequencies, reactance selecting holding keys and circuit connections whereby operation of each key causes a different part of said reactances

100 to be rendered effective in tuning said circuit, a variable reactance for tuning said circuit to selectively receive any desired frequency of a given frequency range including a plurality of said predetermined frequencies, an additional holding key and circuit connections whereby operation of said additional key causes said variable reactance to be rendered effective in tuning said circuit, and means responsive to the operation of any of said holding keys for restoring the one already operated, whereby the circuit may instantaneously be tuned to any one of said plurality of frequencies by the operation of the respective one of the first mentioned holding keys or be conditioned for variable tuning by the operation of said additional holding key.

105 7. In a carrier wave signal receiving system, an electric discharge device, a circuit therefor having input terminals, a plurality of reactance means each having a terminal connected to one of said input terminals, a plurality of switching means each having a contacting member and a plurality of contacts, connections from another of said input terminals to the contacting member of one of said switching means, connections from one contact of said one of said switching means to the contacting member of another of said switching means, connections from another terminal of each of said reactance 120 means to corresponding contacts of respective ones of said switching means, and means responsive to the operation of each switching means for holding said switching means operated until the operation of another of said 125 switching means.

130 8. In a carrier wave signal receiving system according to the preceding claim, another reactance means having a terminal connected to said one of said input terminals and another terminal connected to the contact of the second mentioned switching means corresponding to that contact of the first mentioned switching means connected to the contacting member of said second mentioned switching means.

135 9. In a carrier wave signal receiving system, an incoming circuit, an electric discharge device, an input circuit therefor having input terminals, a plurality of reactance means each having a terminal connected to said incoming circuit, a
